(57) CLAIM

The ornamental design for a toilet bowl skirt, as shown and described.

DESCRIPTION

The nature and intended used of the article being an ornamental design for a skirt that is attached to the front portion of a toilet bowl to alter the appearance of the toilet bowl. FIG. 1 is a front elevational view of the toilet bowl skirt of the present invention;

FIG. 2 is a rear elevational view of the toilet bowl skirt of FIG. 1;

FIG. 3 is a left side elevational view of the toilet bowl skirt of FIG. 1;

FIG. 4 is a right side elevational view of the toilet bowl skirt of FIG. 1;

FIG. 5 is a top plan view of the toilet bowl skirt of FIG. 1;

FIG. 6 is a bottom plan view of the toilet bowl skirt of FIG.

1; and,

FIG. 7 is a top, front, left side perspective view of the toilet bowl skirt shown on a reduced scale in condition of use attached to a toilet bowl.

The broken lines showing of a toilet bowl in FIG. 7 are illustrative purposes only and form no part of the claimed design.
